WIRE STRETCHER AND SPLICER

William J. Alexander, Cora, Wyo.

Application June 7, 1937, Serial No. 146,930

4 Claims. (Cl. 140—123.5)

This invention relates to wire stretchers and splicers, and has for an object to provide a wire stretcher and splicer capable of use with all kinds of wire including barbed wire, in stretching and holding the wire taut and splicing the adjacent ends in an easy and expeditious manner, and with very little effort.

A further object of this invention is to provide a wire stretcher and splicer that is light in weight, yet is strong and sturdy, is simple in construction, inexpensive to manufacture, and extremely efficient in use and service.

Still a further object of this invention is to provide a wire stretcher which is operated by both hands, one hand holding the body of the stretcher, by means of a handle and the other hand operating a crank to tighten the wire so there is no danger of the wire stripping off the stretcher and injuring either hand, particularly in the case of barbed wire.

With the foregoing and other objects in view, this invention comprises the combination, construction and arrangement of parts set forth, disclosed, and claimed in the following specification, taken in connection with the accompanying drawing, wherein like reference numerals denote corresponding parts.

In this drawing:

Figure 1 is a side elevation of the wire stretcher and splicer in operative position.

Fig. 2 is a bottom plan view of Fig. 1.

Fig. 3 is a partly sectional view of the stretcher and splicer after the stretching operation has been completed and the splice is in the process of completion, and

Fig. 4 is a view showing the completed splice.

The wire stretcher and splicer 10 of this invention includes a pair of side walls 11 and 12 shaped substantially as shown and bent toward each other as at 13 where they are joined to one end of the opposite side walls of an inverted channel member 14 having a hook 15 secured adjacent to its opposite end and opening laterally as at 16.

The outer end of the parallel side walls 11 and 12 are joined together by a plate 17 from which extends a pair of prongs 18 bent upwardly to form a loop receiving hook 19. A loop 20 formed on one of the ends of the wire 21 is to be placed over the hook 19 and then the wire is extended rearwardly therefrom, for disposal between the side walls 11 and 12 and through the inverted channel 14, to be held removably in position by the hook 15. The prongs 18 provide a recess 22, through which the other wire 23 ex-

tends and which may be temporarily held after it has been stretched and bent, in order to form the second loop.

After the loop 20 has been put in position, the second wire 23 is threaded through the loop 20 and beneath a wire guide 24 having a V-shaped rear end receiving the wire 23 which is then extended through a diametrical opening 25 in a shaft 26 journalled between the side walls 11 and 12, the shaft 26 having a ratchet wheel 27 and a crank handle 28 secured to one side thereof. A pawl 29 is pivoted to the wall 12 as at 31, to engage the teeth of the ratchet wheel 27 and is held accordingly by a spring 30 to prevent reverse rotation of the shaft 26.

A pawl releasing member 32 may be secured in the side wall 12 for holding the pawl 29 in released position to permit the crank handle 28 to be rotated in a reverse direction to release the wire from the shaft 26. A handle 33 is secured to the side wall 11 so that the wire stretcher and splicer 10 may be conveniently held in the left hand while the right hand rotates the crank handle 28 to tighten the wire 23.

When the wires 21 and 23 have been drawn sufficiently taut, the stretcher and splicer 10 is raised to a 90° angle with respect to the wires, as shown in Figure 3. As this happens, the wire 21 is released from the hook 15 through the opening 16. The stretcher and splicer 10 is then turned to a position parallel to the wire 23, thereby releasing the loop 20 from the hook 19. The stretcher and splicer 10 is then rotated at a 90° angle about the wire 23 so as to coil the same about itself to complete the loop 34 and the splice as shown in Fig. 4. The ratchet wheel 27 meantime has been released to permit the shaft to reverse and thereby release the end of the wire 23 from the shaft.

The novel features and the operation of this device will be apparent from the foregoing description. While the device has been shown and the structure described in detail, it is obvious that this invention is not to be considered limited to the exact form disclosed, and that changes may be made therein within the scope of what is claimed without departing from the spirit of the invention.

Having thus set forth and disclosed the nature of this invention, what is claimed is:

1. A combination wire stretcher and splicer comprising a frame, formed from a pair of spaced parallel side walls, an inverted channel member fixed to and securing said side walls together at one end, a hook member secured to the outer

end of said channel member, a plate bridging and secured to the outer ends of said side walls, a pair of prongs extending forwardly from said plate and inclined upwardly to provide a hook for receiving a splicing loop on one wire, said prongs forming a recess therebetween to provide a notch to receive the other wire therein, in forming a splicing loop thereon, and a shaft journaled between said side walls and having means to receive and secure the last mentioned wire thereto, means to rotate said shaft to tighten said wires, and means to releasably hold the shaft against rotation.

2. A combination wire stretcher and splicer

comprising a frame, formed from a pair of spaced parallel side walls, an inverted channel member fixed to and securing said side walls together at one end, a hook member secured to the outer end of said channel member, a plate bridging and secured to the outer ends of said side walls, a pair of prongs extending forwardly from said plate and inclined upwardly to provide a hook for receiving a splicing loop on one wire, said prongs forming a recess therebetween to provide a notch to receive the other wire therein in forming a splicing loop thereon, a shaft journaled between said side walls and having an end extending through one of said walls, a crank handle and a ratchet wheel secured to the extending end of said shaft, and a releasable pawl engaged with said ratchet wheel for holding the shaft against rotation in one direction.

3. A combination wire stretcher and splicer

comprising a pair of parallel side walls secured together at their ends, a rotatable shaft journaled between said side walls, a crank handle for

rotating said shaft, a ratchet member secured to said shaft, a releasable pawl cooperating with said ratchet member to hold said shaft against rotation in one direction, said shaft having a wire receiving and securing opening extending therethrough, an inverted wire guiding channel member secured to one end of said parallel side walls, a hook member secured to the other end of said side walls to receive a loop in one wire, a V-shaped wire guide secured beneath said hook member to receive and guide a second wire to be threaded through the loop and through the opening of the shaft, so as to be tightened upon rotation of said shaft.

4. A combination wire stretcher and splicer comprising a pair of parallel side walls secured together at their ends, a rotatable shaft journaled between said side walls, a crank handle for rotating said shaft, a ratchet member secured to said shaft, a releasable pawl cooperating with said ratchet member to hold said shaft against rotation in one direction, said shaft having a wire receiving and securing opening extending therethrough, an inverted wire guiding channel member secured to one end of said parallel side walls, a hook member secured to the other end of said side walls to receive a loop in one wire, a wire guide secured beneath said hook member and having a V-shape rear end to receive and guide a second wire to be threaded through the loop and through the opening of the shaft to be tightened by the rotation of said shaft, means to hold the pawl in released position, and a handle member secured to one of said side walls.

WILLIAM J. ALEXANDER.
